PRESSING BUCK

Filed Feb. 18, 1929

INVENTOR
Archie O. Long.
BY
Arthur G. Brown
ATTORNEY

UNITED STATES PATENT OFFICE

ARCHIE O. LONG, OF KANSAS CITY, MISSOURI

PRESSING BUCK

Application filed February 18, 1929. Serial No. 340,836.

My invention relates to presses and more particularly to pressing heads and padded frames adapted for pressing the yokes, cuffs and similar portions of shirts and normally supported and operated by well-known press mechanism used in laundries, the principal objects of the invention being to adapt a press for pressing a plurality of portions of a garment and particularly to adapt a pressing head and a complementary frame for receiving and efficiently pressing the yoke and cuff of a shirt and the portion of the shirt sleeve to which the cuff is attached.

In ordinary laundry presses a separate press is provided for each class of operation, for example presses being adapted by suitable frames and heads for respectively pressing cuffs, yokes, collar bands, and sleeves.

When the functions of several presses have been combined in one, the result has ordinarily been the mounting of several different forms of heads and frames on a single pedestal for operation by single operating means, so that the several portions of a garment may be pressed coincidentally in one operation of the machine. Heretofore, therefore, separate padded frames and pressing heads have been required for each portion of the garment, the economy of assembling a group of heads and frames residing in the reduction of operations by the mechanism.

An object of my invention therefore is to adapt a single combination of pressing head and padded frame for pressing a plurality of items separately or coincidentally, for reducing the number of pieces of equipment in a laundry, the space occupied by equipment, and the expense of installing and operating the same and whereby the number of operations for installing garments in position to be pressed may be minimized and the quality of the work enhanced.

In accomplishing these and other objects of the invention, I have provided improved details of structure, the preferred forms of which are illustrated in the accompanying drawings, wherein:

Fig. 1 is a front elevation of a laundry press embodying my invention.

Fig. 2 is a side elevation of the press, the

pressing head and guide for the vertically slidable buck being shown in section.

Fig. 3 is a perspective view of the buck and pressing head shown in vertically aligned and spaced relation.

55

Fig. 4 is a longitudinal vertical section similar to the view in Fig. 2 of the pressing head, buck and guide illustrating in dotted lines the horizontally adjustable position of the slide for installing garments to be pressed.

Referring in detail to the drawings:

1 designates generally a support comprising a pedestal 2 having spaced vertical arms 3 for supporting a hollow heating head 4 including a transverse member 5 and arch member 6 through which steam may be passed.

A vertical pressure shaft 7 operable by treads 8 and 9 supports a buck 10 including spaced arms 11 and 12 connected at the top by a slide-receiving dome 13, and a padding frame 14 is mounted on a slide rod 15 slidably mounted in bearing openings 16 in the arms 11 and 12. The buck is guided in vertical movement by the lower steam chest. 70 A saddle-like padding support or slide 17 is mounted on the frame 14, and has a portion 18 (Fig. 4 only) extending forwardly from the frame and slidable over the dome 13 when the frame is moved horizontally toward and 80 away from the buck.

The frame is moved toward the buck to bring the padding slide 17 into registry with the upper steam chest by means of the handle 19 on the rod 15, and is restored to outwardly 85 spaced position by a spring 20 anchored to a table 21 projecting from the pedestal, and operating on a lever 22 pivotally connected to the rod at 23 and slidably engaging in a grooved bracket 24 extending from the pedestal. 90

The pressure shaft may be actuated by steam pressure controlled by the treads.

The pedestal, lower steam chest, padding frame, buck and operating means are commonly found in laundry pressing machines, my invention consisting in the padding support and upper steam chest which will now be particularly described.

Padding material 25 conforming to the 100

shape of the padding support is mounted thereon (Fig. 1) to comprise an assembled slide, which will be referred to as the padding bed, for convenience in indicating structure on Figs. 2 and 4 of the drawings.

My padding bed is illustrated as adapted for pressing the yoke, cuff of a shirt, and the portion of a sleeve to which the cuff is attached, and includes three distinctive members or portions 26, 27 and 28. The portion 26 is a yoke-pressing portion and comprises elongated wings 29 diverging downwardly and having an arcuate shoulder 30 extending rearwardly whereby the yoke of a shirt may be positioned on said portion with the neck band of the shirt resting on the shoulder, the shirt thus being extended in horizontal position and normal shape for pressing the yoke as illustrated in Fig. 2, wherein the shirt is shown in dotted lines. The yoke portion 26 further has a forwardly downwardly extending rear edge 31 to receive the shoulders of the shirt.

The intermediate portion 27 of the padding bed is adapted to pressing a cuff, and includes downwardly diverging wings extending in the same plane as the wings of the yoke portion and having lengths substantially equal to the length of a cuff, the lower edge 33 of the portion being therefore inset from the lower edge of the yoke portion.

The padding bed is incut forwardly from the cuff portion to provide a vertical edge 34 with which the sleeve-attached edge of a cuff may register as illustrated in dotted lines in Fig. 3 and the front portion 28 of the bed extends in the plane of the cuff and yoke portions, its wings being abbreviated and having tapering lower edges 35, whereby the placket and cylindrical portion of the sleeve may extend within the diverging planes of the portion 28 to avoid the stretching of the sleeve which would be necessary if the bed were continued forwardly without incutting from the cuff portion, and to permit the cuff to be spread on the cuff portion of the bed.

I form the upper steam chest complementary to the padding bed, having a rear portion 36 adapted to cooperate and overlie the padded rear portion of the frame, an intermediate portion 37, and a forward portion 38 to cooperate respectively with the cuff and front portions of the padding bed.

It is to be understood that the padding support is provided as described for the bed, and the padding is adapted to fit upon the support.

The device being provided as described, the yoke of a shirt may be efficiently pressed, and the shirt may then be repositioned in the same press, with the cuff on the padding bed for pressing against the steam chest, whereby removal of the shirt to another press or bed for pressing the cuff is obviated, and a substantial saving of time and equipment is effected.

Attention is particularly called to the ext-
tent as well as the shape of the padding bed
and upper steam chest whereby a single com-
bination may effectively and efficiently press
the several shirt portions mentioned with a
minimum use of steam, assurance of accuracy
of positioning the garments upon the frame,
and avoidance of wrinkling any part of the
shirt.

What I claim and desire to secure by Let-
ters Patent is:

1. In a laundry press, a pedestal, a frame
movable on the pedestal and adapted to sup-
port a padded bed, said padded bed having a
rear portion comprising downwardly diverg-
ing elongated wings adapted to receive the
yoke of a shirt, an intermediate portion com-
prising shortened arms adapted to receive a
cuff, and a front portion having arms shorter
than the arms of said intermediate portion to
provide a front vertical edge on said inter-
mediate portion with which the sleeve-at-
tached edge of a cuff is adapted to register,
the front portion being adapted for pressing
the portion of the sleeve to which the cuff is
attached, and a bed-receiving head having
portions complementary to said portions of
the padded bed.

2. In a laundry press, a pedestal, and a
movable frame for supporting a padded bed,
said padded bed including a rear member
having downwardly diverging elongated
wings provided with arcuate shoulders at the
rear ends thereof, an intermediate member
comprising wings having lower edges offset
from the lower edges of the first named mem-
ber, and a front member comprising wings
having lower edges offset from the lower
edges of the intermediate member, and a head
having members complementary to said
members of the padded bed.

3. In a device of the character described,
a head comprising downwardly diverging
wings having downwardly inwardly offset
front edge portions and a bed comprising
downwardly diverging wings having front
edge portions downwardly inwardly offset
sufficiently to conform substantially to the off-
set front edge portions of said head.

4. A device of the character described in-
cluding a padded bed comprising downward-
ly diverging wings having vertical rear edges
provided with inclined shoulders at the up-
per ends of said edges.

5. A device of the character described in-
cluding a padded bed having downwardly
diverging outer faces and a rear edge includ-
ing a downwardly forwardly inclined por-
tion, and a head including a portion having a
rear edge conforming substantially to said
inclined portion of said padded bed edge.

6. In a device of the character described, a
bed having diverging side faces including a
forwardly projecting front end portion hav-
ing backwardly and downwardly inclined

lower edges and a portion having a front edge with which the sleeve attached edge of a cuff is adapted to register spaced rearwardly from the front edge of the front end portion,
5 and a head having side faces conforming to and of sufficient extent to cover said bed faces and including a front portion having side faces of sufficient length to cover said front end portion of the bed and having lower edges extending to the lower edges of the front end portion of the bed.
10

In testimony whereof I affix my signature.
ARCHIE O. LONG.
